UNITED STATES PATENT OFFICE

JOHN K. NORTHRUP, OF BRENTWOOD HEIGHTS, CALIFORNIA

FLUSHING VALVE

Application filed February 20, 1928. Serial No. 255,617.

My invention relates to manhole valves for use in flushing sewer systems, and its broad purpose is to provide a watertight valve which will permit water to be stored in a manhole without wastage, and which will permit the water thus held to be quickly and easily discharged to produce the flushing action.

An object of my invention is to provide a valve requiring a minimum of service.

Another object of my invention is to provide an efficient valve having few and inexpensive parts.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Flushing is usually accomplished in sewerage systems either by self-dumping tanks, typified by that described in my co-pending application, Serial No. 25,918, filed April 25, 1925, or by means of a flushing manhole. The latter usually comprises a manhole of the ordinary type having an outlet near the bottom leading into the sewer and covered by a flap valve. An inlet pipe of fairly large size and provided with a manually operated cock admits water to the manhole. An attendant visits the manhole periodically, first filling it with water, then opening the flap valve by means of a chain attached thereto and thereby flushing the sewer.

Filling the manhole with water is a time consuming operation, as 200 gallons or more must be allowed to run in. The supply pipe at best cannot approach the outlet pipe in capacity, and the flap valves are seldom if ever watertight, and frequently permit the water to escape as fast as it is admitted. From one quarter to one half an hour of the

attendant's time is therefore required to fill the manhole, emptying it requiring about thirty seconds.

My invention provides a positive acting watertight valve. The manhole may therefore be filled from a small supply pipe, controlled by the ordinary type of float valve which closes when the water has reached a predetermined level. This is precluded in the usual system because of the enormous wastage of water through the leaky flap valves. The attendant's duties with my valve are therefore merely to open the valve while the flushing takes place, close it again, and continue on his rounds. Actual experience has shown that the number of attendants required where my valves are installed is only one tenth those needed under the older system.

Referring to the drawings:

Fig. 1 is a plan view, and Fig. 2 is a central vertical sectional view of an embodiment of my invention as installed in a manhole. The full lines show the valve closed and the dotted lines in a partly open position. To conserve space portions of the manhole are cut away in the drawing.

Broadly considered, my valve comprises a mounting ring which is cemented over the end of the sewer pipe leading from the manhole. An annular valve seat is formed on the end of this ring. Loosely hinged to the ring is a valve disk or gate which hangs normally as so to cover the valve seat. The valve is preferably provided with a slightly resilient gasket to aid in forming a watertight closure.

An arm extends outwardly from near the center of the disk and pivotally mounted to the end of this arm is a weighted lever. The short arm of the lever engages with a fulcrum supported by the mounting ring. The parts are so proportioned that the reaction of the weighted arm against the fulcrum lifts the loosely mounted gate from its hinge pin.

and forces it, with greatly augmented pressure, against the valve seat.

A chain attached to the end of the lever allows it to be raised, first disengaging the 5 fulcrum, and then turning the valve on its hinge to permit the water to escape.

In terms of greater detail, a preferred embodiment of my invention comprises a mounting ring 6, preferably of cast iron, 10 which is cemented to the end of the outlet pipe 7 of the manhole 8. Formed on the end of this ring is a lip 9 which is machined true and which forms the valve seat.

On the upper side of the mounting ring is 15 a pair of lugs 11 which are drilled to receive the hinge pin 12, preferably of brass or other rust-proof material. The hinge pin passes loosely through slots 13 in the brackets 14, attached to the valve disk 16, which therefore 20 normally hangs in front of the valve seat. The valve disk is preferably flat, and cemented or bolted to its surface is the rubber or composition gasket 17.

Extending outwardly from the valve disk 25 is the arm 18 to which the lever 19 is hinged by the pin 21. I prefer to make the arm double as shown in the drawing but it is obvious that a single arm could be employed. The long arm of the lever has a weight 22 30 adjacent its distal end, and an eye 23 is provided for attaching a chain 24 by which the valve is operated from the manhole opening. The short arm of the lever makes an obtuse angle with the long arm, and extends upwardly, carrying a transverse round rod 26 35 which bears against fulcra to seal the valve.

The fulcra are formed by the inturned ends 27 of the bars 28. The bars are secured to the mounting ring and their outer ends may be 40 supported by the small masonry abutments 29. The ends of the bars are so turned that the fulcrum surfaces are not parallel with the plane of the valve seat, but are inclined thereto at an acute angle of the order of 20°.

When the valve is closed, with the weight 45 hanging freely, the round rod 26 rests against the fulcrum surfaces, and the couple acting on the short lever arm thru the rod and the hinge pin 21 forces the valve closed. The 50 principal component of this couple is horizontal, but due to the slant of the fulcra there is also a vertical component, which tends to lift the valve from the hinge pin 12, thus preventing any accidental catching that 55 might tend to hold the upper edge of the valve open and cause water wastage.

The action of the valve will now be apparent. When the attendant lifts on the chain 24 the lever rotates about the pin 21, 60 disengaging the rod 26 from the fulcra and thus releasing the sealing pressure on the valve. The rod 26 strikes the arm 18, which serves as a stop, and further traction on the chain rotates the valve disk on its hinge and 65 liberates the impounded water. Relaxing

the chain first allows the valve disk to drop into position in front of its seat, and then seals it by the engagement of the lever with its fulcra as previously described.

The valve has been described and shown as 70 mounted vertically. It is evident, however, that by using a straight lever instead of a bent one, a horizontal mounting would be equally satisfactory.

I claim:

1. In a flushing valve, a valve seat, a rigid fulcrum adjacent the seat, a valve gate adapted to cover said seat, means for mounting said valve movably over said seat, and a weighted lever pivotally connected to said gate and adapted to engage the fulcrum to press said gate against said seat and to support a portion of the weight of said valve.

2. In a flushing valve, a valve seat, a gate 80 loosely hinged adjacent said seat and adapted to engage therewith, a fulcrum surface disposed at an acute angle to the plane of said seat, and a weighted lever pivotally mounted on said gate and adapted to engage said fulcrum surface.

3. In a flushing valve, a valve seat, a gate 85 loosely hinged adjacent said seat and adapted to engage therewith, a fulcrum surface rigid with respect to said seat, and a weighted lever pivotally mounted on said gate and adapted to engage said surface.

4. A flushing valve comprising a mounting ring, a valve seat formed on said ring, a valve gate loosely hinged to said ring, an arm extending outwardly from said valve gate, a 100 weighted lever pivotally mounted on said arm, an arm extending from said mounting ring and a fulcrum on said latter arm engaging said lever.

5. In a flushing valve, a valve seat, a movably mounted valve gate adapted to cover said seat, a fulcrum surface positioned in front of said seat, and a weighted lever pivotally connected to said gate and projecting outwardly therefrom and adapted to engage said 105 fulcrum to press the gate against the seat.

6. A flushing valve comprising a valve seat, a valve gate adjacent said seat, a hinge for mounting the gate for outward movement from the seat, a fulcrum adjacent the seat, and a lever connected to the gate and adapted to engage the fulcrum to press the gate against the seat and to lift a portion of the weight of the valve from the hinge.

7. A flushing valve comprising a valve seat, a fulcrum mounted on the seat, a valve gate adjacent said seat, a loose hinge for mounting the gate for outward movement from the seat and permitting alinement of said valve and seat, and a lever connected intermediate its 120 ends to said gate and cooperating with the fulcrum to press the gate against the seat.

8. A flushing valve comprising a mounting ring, a valve seat formed on the ring, a valve gate loosely hinged on the ring, a weighted 125

lever pivotally connected to the gate, and a fulcrum on the ring against which the weighted lever reacts to press the gate against the seat.

5 9. A flushing valve comprising a valve seat, a valve gate hinged to the seat, a weighted lever fulcrumed upon said valve seat, and means connecting the lever to the gate to permit the weight of the lever to exert a closing force on the gate.

10 In testimony whereof, I have hereunto set my hand.

JOHN K. NORTHROP.
